[57] ABSTRACT

Fluid pressure device including axially positionable shaft means and rotary valve means. Said shaft means and said rotary valve means are independently and axially positionable in housing means having first and second end portions. Closure means is removably secured to said first end portion of said housing means. Stationary valve means is removably secured to said second end portion of said housing means. Said shaft means rotates said rotary valve means relative to said stationary valve means. Rotatable and orbitable fluid pressure means is secured to said stationary valve means. Said stationary valve means and said rotary valve means control the flow of fluid to and from said rotatable and orbitable fluid pressure means. Positionable means including said closure means fixes the axial position of said shaft means in said housing means. Said rotary valve means has an axial position fixed by said stationary valve means against which it is rotated, whereby said rotary valve means and said shaft means are axially fixed independently of each other. Said rotary valve means and said shaft means have mechanical connection means therebetween which includes non-rotative connection means to rotate said rotary valve means by said shaft and axially slidable connection means to accommodate for axial dimensional tolerances between said shaft means and said rotary valve means incident to their being axially positionable independently of each other.

FLUID PRESSURE DEVICE INCLUDING AXIALLY POSITIONABLE SHAFT MEANS AND ROTARY VALVE MEANS

BACKGROUND OF THE INVENTION

This application is an improvement on the device disclosed in my application, Ser. No. 880,677, filed Nov. 28, 1969 now U.S. Pat. No. 3,592,233.

The matching of dimensional tolerances between two independently mounted parts is substantially impossible upon a production basis. An example of two independently mounted parts is found in applicant's fluid pressure device, wherein the shaft and rotary valve are axially positionable independently of each other. In the present application, applicant does not attempt to match dimensional tolerances, as such, but provides a solution by accommodating for axial dimensional tolerances between the shaft and the rotary valve means, incident to their being axially positionable independently of each other.

An object of my invention is to accommodate for axial dimensional tolerances between an axially, independently positionable shaft and an axially, independently positionable rotary valve.

Another object is to obtain such accommodation by providing mechanical connection means between the shaft and rotary valve, wherein said mechanical connection means includes non-rotative connection means to rotate the rotary valve by said shaft and axially slideable connection means to accommodate for axial dimensional tolerances between the shaft and the rotary valve incident to their being axially positionable independently of each other.

SUMMARY OF THE INVENTION

The invention constitutes fluid pressure device including axially positionable shaft means, axially positionable rotary valve means, housing means for said shaft means and said rotary valve means, said housing means having first and second end portions, closure means removably secured to said first end portion of said housing means, stationary valve means removably secured to said second end portion of said housing means, said shaft means rotating said rotary valve means relative to said stationary valve means, rotatable and orbitable fluid pressure means secured to said stationary valve means, said stationary valve means and said rotary valve means controlling the flow of fluid to and from said rotatable and orbitable fluid pressure means, positionable means including said closure means for fixing the axial position of said shaft means in said housing means, said rotary valve means having an axial position fixed by said stationary valve means against which it is rotated, whereby said rotary valve means and said shaft means are axially fixed independently of each other, said rotary valve means and said shaft means having mechanical connection means therebetween, said mechanical connection means including non-rotative connection means to rotate said rotary valve means by said shaft means and axially slideable connection means to accommodate for axial dimensional tolerances between said shaft means and said rotary valve means incident to their being axially positionable independently of each other.

BRIEF DESCRIPTION OF THE DRAWINGS

Other objects and a fuller understanding of this in-

vention may be had by referring to the following description and claims, taken in conjunction with the accompanying drawings, in which:

FIG. 1 is a top view of a fluid pressure device embodying the features of my invention;

FIG. 2 is a longitudinal sectional view of FIG. 1, except that the section through the rotary valve is taken along a line other than a vertical center line, and showing a section illustrating both the outside and inside rotary valve ports which appear unshaded;

FIG. 3 is a left-hand side view of the rotary valve only, taken along the line 3-3 of FIG. 2, showing principally a female socket of non-circular configuration, the rotary valve being rotated 90 degrees from the position shown in FIG. 2; and

FIG. 4 is a representation of a male shank provided on a terminal portion of a hollow shaft adapted to slidably fit within the female socket of the rotary valve, the male shank being rotated 90° from the position shown in FIG. 2 to match the angular position of the female socket in FIG. 3.

For clarity of invention, the usual static seals and the seal for the rotating shaft are not shown. Also, all wear parts are made of hardenable surfaces and are well lubricated by the operating fluid.

With reference to the drawing, the fluid pressure device in which my common bearing means may be incorporated, comprises generally a main housing 20 having substantially a square cross-section. A mounting flange 21 may be secured to the left-hand end of the housing by means of suitable screws 26 (one of which is shown in FIG. 1). The housing 20 is hollow from end-to-end, and intermediate the ends of the hollow housing there is provided an annular internal rim 22 which generally separates the hollow-housing into a left-hand end compartment and a right-hand end compartment. Rotatively mounted in the left-hand end compartment is a main load shaft 25 having an axis substantially coinciding with the longitudinal axis of the fluid pressure device. A bushing 27 and a rotary valve 28 are mounted in the right-hand end compartment. On the right-hand end of the hollow housing, there is mounted a square stationary valve member 29 by means of suitable screws 30. The rotary valve is adapted to be rotated relative to the stationary valve member 29 for controlling the entrance of fluid to and the exit of fluid from a stator-rotor mechanism 31 comprising a stator 32 and a rotor 33. An end cap 34 encloses the stator-rotor mechanism 31. The stator-rotor mechanism 31 and the end cap 34 are secured to the stationary valve member 29 by means of screws 35. Fluid is delivered to and from the housing 20 through a pair of fluid ports 23 and 24. An actuating shaft 36 interconnects the main shaft 25 with the rotor 33 of the stator-rotor mechanism 31 and is adapted to transmit torque therebetween.

The main shaft 25 comprises an enlarged internal portion having a reduced external portion 41 extending axially outwardly of the main housing 20 through the mounting flange 21. The enlarged internal portion of the main shaft is supported preferably by tapered roller bearings 42 and 43 disposed side-by-side with the bearing 42 disposed oppositely to that of the tapered roller bearing 43. Thus, the tapered roller bearings 42 and 43, in combination with each other, provide for radial thrust as well as for end thrust in both axial directions, with the tapered roller bearing 42 disposed to take the greater part of the radial load. A tightening nut 54

which threadably engages male threads 55 secures the bearings 42 and 43 against axial movement upon the main shaft. The tightening nut 54 may be provided with a built-in locking feature to prevent loosening.

As shown, the bearings 42 and 43 are secured against axial movement in the housing by axial fixation means, indicated by the reference character 60. The axial fixation means 60 is located within a bore 62 of the flange and comprises an annular V-shaped or pointed rib which axially abuts against a transversely disposed solid abutment wall of the bearing 42. The rib may be constructed either integrally with or as a separate part from the flange 21. By pressing the flange 21 against the end of the housing 20 during assembly, the pointed rib is coined against the bearing 42, with the result that the fixation means accommodates for axial tolerance in matching the position of the bearings in the housing. The pressure required to coin the axial fixation means is greater than the end-wise thrust load to which the bearing means 42 may be subjected in operation, in which case the bearings 42 and 43 are resisted against axial movement in operation. The main shaft is entirely supported by the two tapered roller bearings 42 and 43. The reduced external shaft portion 41 where it passes axially through the end mounting flange 21 is not journalled therein but rotates therein with a small radial clearance which is adapted to be sealed off by suitable shaft seal means, not shown. The axial fixation-means 60, after being coined, provides a fluid seal between the housing and the flange.

The bearing 42 and 43 constitute common bearing means for the main shaft 25 and the rotary valve 28. The common bearing means directly support the main shaft 25 and indirectly support the rotary valve 28 through extension drive means comprising a hollow shaft 44 carried by the load shaft 25. The hollow shaft 44 extends axially from the load shaft 25 in the left-hand compartment into the right-hand compartment for driving connection with the rotary valve 28 for rotating same relative to the stationary valve 29. The hollow shaft 44 terminated with a male shank 45 which slidably fits within a female socket 46 provided in the rotary valve 28, see FIGS. 2, 3 and 4. This connection comprises a non-rotatable connection and rotates the rotary valve upon rotating by the main shaft. The connection also provides slidable axial movement between the rotary valve 28 and the hollow shaft 40 to accommodate for axial movement of the load shaft without interfering with the operation of the rotary valve. The axial slidable movement which is permitted between the male shank 45 and the female socket 46 is greater than the maximum distance that the load shaft 25 may move in an axial direction during operation. As illustrated in FIG. 2, the rotary valve 28 and the second compartment means in which it is mounted has a radial clearance 47 therebetween to accommodate for radial movement of the load shaft 25 without interfering with the operation of the rotary valve. The radial clearance 47 is greater than the maximum distance that the load shaft 25 may move in a radial direction during operation.

The operation of the rotary valve relative to the stationary valve provides for controlling the entrance of fluid to and the exit of fluid from the stator-rotor mechanism. The action of the rotary valve 28 in commutation with the stationary valve is such that there is a first series of commutating fluid connections between the

fluid port 23 and the stator-rotor mechanism and a second series of commutating fluid connections between the stator-rotor mechanism and the fluid port 24. The stationary valve 29 has a plurality of circumferentially disposed openings 48 which extend therethrough to provide for fluid communication between the rotary valve 28 and the stator-rotor mechanism. The commutating valve action, and the flow of fluid between the fluid ports 23 and 24 and the stator-rotor mechanism is substantially the same as that shown and described in my U.S. Pat. No. 3,405,603. Thus, in the present application, the annular channel around the outside of the rotary valve is in constant communication with the fluid port 23 and the central space inside the rotary valve is in constant communication with the fluid port 24 through opening means 50 in the hollow shaft 44. Likewise, the section through the rotary valve in FIG. 2 of the present application is taken along a line substantially the same as the line 23-24 of my patent.

As shown and described in the present invention, the rotary valve 28 functions without interference from axial and radial thrust loads on the load shaft 25, even though it is rotatively supported by the same bearings that support the load shaft.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. Fluid pressure device including axially positionable shaft means, axially positionable rotary valve means, housing means for said shaft means and said rotary valve means, said housing means having first and second end portions, closure means removably secured to said first end portion of said housing means, stationary valve means removably secured to said second end portion of said housing means, said shaft means rotating said rotary valve means relative to said stationary valve means, fluid pressure means including first and second relatively rotatable elements, one of said elements being secured to said stationary valve means, said stationary valve means and said rotary valve means controlling the flow of fluid to and from said fluid pressure means, positionable means including said closure means for fixing the axial position of said shaft means in said housing means, said rotary valve means having an axial position fixed by said stationary valve means against which it is rotated, whereby said rotary valve means and said shaft means are axially fixed independently of each other, said rotary valve means and said shaft means having mechanical connection means therebetween, said mechanical connection means including non-rotative connection means to rotate said rotary valve means by said shaft means and axially slideable connection means to accommodate for axial dimensional tolerances between said shaft means and said rotary valve means incident to their being axially positionable independently of each other, said stationary valve means having passage wall means in communication with said fluid pressure means, said rotary valve means having external fluid chamber means therearound and internal valve fluid chamber means therewithin, said rotary valve means having first fluid

conduction means in constant communication with said external chamber means and in registerable communication with said passage wall means in said stationary valve means and having second fluid conduction means in constant communication with said internal valve chamber means and in registerable communication with said passage wall means in said stationary valve means, said rotary valve means also having a central opening in constant fluid communication with said internal valve chamber means and through which fluid may flow to and from said internal valve chamber means, said shaft means including hollow shaft body means defining internal shaft fluid chamber means in constant fluid communication with said internal valve fluid chamber means, said hollow shaft body means having passageway wall means through which fluid may flow to and from said internal shaft fluid chamber means.

2. The structure of claim 1, wherein said rotary valve means has first and second axially spaced body portions, said first body portion having a rotary valve face sealingly engaging said stationary valve means, said second body portion having female socket means therein, said shaft means terminating in male shank

means and fitting within said female socket means, said mechanical connection means including said male shank means and said female socket means.

3. The structure of claim 2, wherein said male shank means comprises a hollow substantially cylindrical body having a shank drive portion.

4. The structure of claim 3, wherein said female socket means comprises an internal substantially cylindrical wall having a socket drive portion, said shank and socket drive portions interfitting with each other, said mechanical connection means including said shank and socket drive portions.

5. The structure of claim 1, wherein said fluid pressure means includes rotor means.

15 6. The structure of claim 5, wherein said shaft means includes a hollow body having first female spline teeth therein, said rotor means having second female spline teeth therein, an actuating shaft having first and second shaft end portions, said first shaft end portion having first male spline teeth thereon fitting within said first female spline teeth, said second shaft end portion having second male spline teeth thereon fitting within said second female spline teeth.
